UNITED STATES PATENT OFFICE.

JOHNSON M. FRAZIER, OF PHILADELPHIA, PENNSYLVANIA.

DESIGN FOR A GLASS PITCHER.

48,351.

Specification for Design.

Patented Dec. 28, 1915.

Application filed September 7, 1915. Serial No. 49,403. Term of patent 7 years.

To all whom it may concern:

Be it known that I, JOHNSON M. FRAZIER, a citizen of the United States, residing at Philadelphia, in the county of Philadelphia and State of Pennsylvania, have invented a new, original, and ornamental Design for Glass Pitchers, of which the following is a specification, reference being had to the accompanying drawing, forming part thereof.

In the drawings, Figure 1, is a view in side elevation of the glass pitcher showing

my new design. Fig. 2, is a front view thereof, and Fig. 3, is a top or plan view of Fig. 1.

I claim:

The ornamental design for a glass pitcher, as shown.

JOHNSON M. FRAZIER.

Witnesses:

WILLIAM J. JACKSON,
HELEN M. BYRNE.
